UNITED STATES PATENT OFFICE.

JACOB S. JAMMER, OF CUMBERLAND, MARYLAND, ASSIGNOR TO WESTERN ELECTRIC COMPANY, INCORPORATED, OF NEW YORK, N. Y., A CORPORATION OF NEW YORK.

REPEATER.

Application filed February 1, 1923. Serial No. 616,243.

This invention relates to repeaters and more particularly to high gain repeaters for commercial purposes.

In telephone repeater circuits, it is customary to mount the amplifying apparatus comprised in a repeater circuit in compact form and to terminate the various parts of the circuit which require connection to apparatus outside of the repeater unit itself upon a terminal block where the several terminals are associated quite closely together. Consequently the input circuit terminals are ordinarily not far removed from the output circuit terminals. In the ordinary repeater 10 heretofore used, this arrangement was entirely satisfactory but where large amplifications or gains are required, singing within the repeater results from the large potential and current differences required between various parts of such a compact repeater structure.

Repeaters employing electron discharge devices as the amplifying elements are widely used in ordinary telephone systems and, especially in the United States, a more or less standardized repeater unit has been developed for this service. This unit has been designed for use upon ordinary long distance telephone lines and permits of satisfactory telephone transmission when inserted in the line at intervals of approximately 300 geographical miles. A new problem is presented, however, when these same lines are to be used for telephone and telegraph transmission by means of carrier currents having frequencies many times those of ordinary voice frequencies. The attenuation of carrier frequencies resulting from their transmission over long distance lines is very much greater than those of voice frequencies and therefore the problem of amplification is considerably more difficult of solution. The solution of this problem prior to the present invention consisted in locating the repeater stations closer to one another geographically. This solution necessitated the construction of special repeater stations on transmission lines which were to be used both for voice and carrier frequencies.

This invention makes possible the elimination of these special repeater stations with a consequent increase in operating efficiency and reduction in operating cost. The same repeater attendants may be available for both the voice frequency repeaters and the

carrier current repeaters. Another important advantage of the use of a high gain repeater according to this invention lies in the possible reduction in the number of repeater test stations. Ordinarily, the same 60 test equipment can be used for a large number of repeaters providing they are located at the same repeater station. Consequently, if all of the repeaters associated with a given line or plurality of lines passing through a 65 given station, both voice frequency and carrier current, can be located at that station, an economy in testing equipment can be effected.

An object of this invention is to increase 70 the amplification or gain of which repeaters are capable. Another object is to make possible a reduction in the number of repeater points in a commercial electrical transmission system by increasing the amplification 75 of each repeater so as to span a greater geographical distance. Still another object is to supply polarizing potential for the input circuits of several electron discharge devices in a novel and efficient manner. 80

A feature of this invention is an operative repeater having a large amplification or high gain, which still retains the advantages of a unitary and compact structure of former lower gain repeaters. Another feature 85 is a two-way carrier current repeater having high gain characteristics wherein one group of frequencies may be transmitted in one direction and a different group of frequencies in the other direction. A further feature 90 is a carrier current repeater which spans the same geographical distance as the present voice frequency repeaters used on the same types of lines.

A typical arrangement of circuits for a 95 carrier current repeater known and used previously to this invention is shown and described in Patent No. 1,413,357, issued to P. A. Raibourn, April 18, 1922. This arrangement comprises a single amplifying 100 structure in each branch of a two-way repeater having filter sections connected to both its input and output circuits between the two sections of the transmission line.

According to the present invention, a two-way carrier repeater may have the amplifying structures arranged in two stages, each 105 of which is a unitary structure having input and output circuit terminals located on a single terminal block. The grouping filters 110

for separating oppositely directed transmissions for the two oppositely directed branches consist of three elements one each located ahead of, between, and following the two amplifying structures. An equalizer element may also be provided. All of the elements for a given branch may be mounted on vertical supports in the order indicated above having the equalizer element placed 10 between the first filter section and the first amplifying structure. The several elements are so interconnected that conductors carrying different values of current or which are at widely different potentials are sufficiently separated physically to prevent feed back of energy from the output circuit of one amplifying device to its input circuit or to the input circuit of the preceding amplifying device so as to prevent singing.

15 A method of associating such a repeater with ordinary telephone transmission line for multiplex operation is described in an article by Messrs. Colpitts and Blackwell entitled, "Carrier current telephony and 20 telegraphy" published in the Transactions of the American Institute of Electrical Engineers, volume XL, 1921.

The novel features which are considered 25 characteristics of this invention are set forth with particularity in the appended claims. The invention itself, however, both as to its organization and method of operation together with further objects and advantages thereof will best be understood by reference to the following description taken 30 in connection with the accompanying drawings in which Fig. 1 illustrates a two-way carrier current high gain repeater. Fig. 2 shows a convenient arrangement of the elements of the repeater of Fig. 1. Figs. 3 and 4 illustrate certain details adapted for alternate use with the repeater of Fig. 1.

Referring now to Fig. 1, a two-way carrier current repeater is shown with two branches A and B connected for the two way transmission of different frequency range groups of carrier waves between transmission lines ML^1 and ML^2 , as explained in the Raibourn patent hereinbefore mentioned. One group of frequencies is transmitted from line ML^1 to line ML^2 through branch A while another group of frequencies is transmitted in the opposite direction from line ML^2 to line ML^1 through branch B. The direction of transmission is indicated by arrows.

Branch A comprises a filter section FA^1 , an equalizer element EA, an amplifying structure A^1 , a second filter section FA^2 , an amplifying structure A^2 and a third filter section FA^3 . The filter sections are each adapted to pass the same range of frequencies. Preferably they offer negligible attenuation to current of the frequencies to be transmitted and very high attenuation to

currents of all other frequencies. In other words they are uniformly selective of the plurality of frequencies to be transmitted. These filter sections may be of the same general character as the well known band filters disclosed in patent to Campbell No. 1,227,113, May 22, 1917. Filters of this type consist in general of a plurality of recurring sections having series and shunt reactances designed, according to well known laws, for the range of frequencies of the currents which the filters are to transmit.

The equalizer element EA is inserted to compensate for the unequal attenuation of different frequencies by the transmission line ML^1 . A network suitable for this apparatus is shown in Fig. 3 and comprises resistances 19 and 20 connected in series with a loop tuned circuit comprising inductance 21 and capacity 22. The inductance and capacity of this network are so proportioned that the loop circuit is resonant at substantially the highest frequency which is to be transmitted to the amplifying structures, consequently, this network provides a by-pass for the lower frequencies in proportion to their remoteness from the frequency to which the loop is tuned. The higher frequencies are substantially unaffected and are impressed with full amplitude upon the input circuit of amplifying structure A^1 .

Another form of equalizer element EA, which for many purposes is the preferred form, is shown in Fig. 4. This form employs both a shunt section and a series section. The shunt section consists of resistance 19 and inductance 48 connected in series with the loop tuned circuit comprising inductance 21 and capacity 22. The series section consists of three branches connected in parallel. Resistance 44 constitutes one branch; capacity 45, a second; and inductance 47 and capacity 46 connected in series with each other, a third. The loop tuned circuit 21-22 and the series tuned circuit 46-47 are each adjusted to resonance at approximately the highest frequency to be transmitted. The values of the other elements are so chosen that the transmitted current is substantially proportional to the frequency thereof. The advantage of this form of equalizer element lies in its substantially uniform impedance, viewed from the line, to currents of all frequencies for which it is designed.

The same forms of equalizer elements are suitable for element EB. The direction of transmission through these elements are indicated by dotted arrows.

The amplifying structure A^1 is somewhat similar to that disclosed in patent to E. H. Colpitts, No. 1,128,292, February 16, 1915, but it must be adapted to take care of the wide range of frequencies encountered in a

carrier current system. It comprises two stages of amplification, the first of which consists of electron discharge devices 23 and 24 while the second stage consists of devices 25 and 26. Each pair of devices are connected in push-pull relationship as explained in the Colpitts and Blackwell article supra. Plate current for the first stage is furnished by battery 27 in parallel through choke coils 28 and 29. Plate current for the second stage is supplied by battery 30 in parallel through choke coils 31 and 32. Polarizing potential for the first stage is furnished by the battery 33 through choke coil 34 and similar potential for the second stage by battery 35 through choke coil 36. Well known resistance coupling consisting of resistances 37 and 38 is used between stages.

Energy from the line ML^1 is impressed upon the input circuit of amplifying structure A^1 by means of balanced potentiometer 39 and shielded input transformer 40. Output energy from amplifying structure A^1 is transmitted to a second filter section FA^2 by means of shielded transformer 41.

The balanced potentiometer 39 has two movable contacts, which are at all times equally distant from the ends of the resistance element. The potentials with respect to ground of the conductors connected to these movable contacts are consequently equalized and a balanced system results.

The shielded transformers in this system, such as transformer 40, have a metallic shield between the line windings and the drop windings. The line windings are those windings which are connected directly or indirectly to the line, while the drop windings are connected to apparatus, such as the repeater in this instance. By connecting this shield to ground a by-pass around the repeater is provided for currents which may result from foreign potentials between the line conductors and ground. Were it not for these shields these currents would find a path through the repeater by way of the capacity between the line and drop windings.

A series parallel arrangement is used for heating the filaments from battery 42. Resistances 43 are employed to protect the filaments of the electron devices in either stage from an excessive flow of current in case the filament of one of the electron devices in the same stage accidentally burns out.

The amplifying structure A^2 also comprises a balanced arrangement of electron discharge devices such as described in the Colpitts patent hereinbefore mentioned. A single stage of amplification is employed however. The two electron discharge devices 50 and 52 are connected in parallel with each other on one side, while discharge devices 51 and 53 are connected in parallel with each other on the other side. Plate

current for all of these devices is furnished by battery 54 through choke coils 55 and 56. Grid polarizing potential for devices 50 and 51 is supplied by battery 57 through choke coil 58, while grid polarizing potential for devices 52 and 53 is supplied by battery 59 through choke coils 60 and 61. The filaments are heated from battery 62 in a manner similar to that of amplifying structure A^1 . Energy is impressed upon the amplifying structure A^2 by shielded input transformer 63. Output energy from amplifying structure A^2 is transmitted by shielded transformer 64.

The circuits of amplifying structures B^1 and B^2 are identical with those of amplifying structures A^1 and A^2 respectively and need not be further described in detail.

The cathode heating current for all of the devices may be obtained from a single source which practice is common in the telephone systems of the United States. Likewise, space current for all of the devices may be obtained from a single source. The polarizing potentials for the input circuits of all of the devices may also be obtained from a single polarizing potential source. Reference may be made to patent to Clark No. 1,385,777, July 26, 1921, in this connection.

In the arrangement of the present invention a choke coil is included in each polarizing potential circuit. These choke coils offer high impedance to the currents to be amplified. The use of a common source of polarizing potential reduces the plant upkeep to a minimum and enables ready location of faults in the supply source. These choke coils prevent cross-talk and singing which might otherwise result from the use of the common polarizing source.

In the amplifying structures A^2 and B^2 it is to be noted that the polarizing potentials for the separate pairs of grids are supplied through separate circuits. The pairs of grids are connected in parallel by means of condensers 65, 66. By this arrangement each grid may be given its proper polarizing potential and, if desired, the potential may be obtained from a source common to all of the devices. Previously when two electron devices which had their cathodes connected in series with each other were connected in parallel with respect to their input circuits, a supplemental polarizing potential source was connected into the grid circuit of one of the devices to compensate for the potential drop across the cathode of the other devices. Defective operation of such repeaters, the cause of which was sometimes difficult to locate, would often be due to this supplemental battery. This trouble is eliminated by the arrangement of this invention.

Fig. 2 shows a convenient method of mounting the several elements of Fig. 1 to

provide a compact high gain repeater which will possess efficiency without singing. Corresponding parts of the two figures are designated by like reference characters. As shown, the several elements of branch A are mounted one above the other on vertical supporting frames 80 and 81. The various elements are arranged from top to bottom in the order of their connection in branch A from left to right. Similarly, the elements of branch B are mounted on vertical supporting members 81 and 82. The several elements are arranged from top to bottom in the order of their connection in branch B from right to left. Transmission lines ML^1 and ML^2 are brought in from the top. A pair of conductors 5 are connected from the line ML^1 to the input terminals of filter element FA^1 . Another pair of conductors 18 extends to the output terminals of filter element FB^3 . A pair of conductors 12 connect the line ML^2 to the input terminals of filter element FB^1 , while a pair of conductors 11 connect the line ML^2 to the output terminals of filter element FA^3 . Connections between the several elements of branch A are made by conductors 6, 7, 8, 9 and 10. Similarly, connections between the elements of branch B are made by conductors 13, 14, 15, 16 and 17. By means of this arrangement, conductors 18 may be physically separated from the interconnecting conductors 6, 7, 8, 9 and 10 and so reduce the possibility of singing by the repeater as a whole due to the feed back of energy from conductors 18 to conductors 7 and 9 which connect to the input terminals of amplifying structures A^1 and A^2 . For the same reason, conductors 11 may be physically separated from conductors 14 and 16 of branch B. The arrangement also permits of a separation of conductors 7 and 10 and so prevents the feed back of energy from the output circuit of amplifying structure A^2 to the input circuit of amplifying structure A^1 . As previously explained, the individual amplifying structures do not produce sufficient amplification or gain to cause singing within the individual structures, and according to this invention these several structures are so associated that any desired gain may be affected without singing.

In the Raibourn patent hereinbefore mentioned, transfer of energy from one branch to the other is prevented not only by the grouping filters but also by a balanced connection between the two branches. In the preferred embodiment of this invention as hereinbefore described, the balanced transformers are eliminated and singing around the repeater is prevented solely by the grouping filters.

In a repeater arranged according to this invention, an amplification or gain compensating for the attenuation of 45 miles of standard telephone cable can be accom-

plished for frequencies as high as 33,000 cycles per second. At the highest frequency in the transmission range of branch A, for example, the loss in filter section FA^1 is 1.5 miles; in equalizer EA, 0.5 miles; in filter section FA^2 , 1.5 miles; and in filter section FA^3 , 1 mile. The gains in the same branch provided by amplifying structure A^1 is 31.5 miles while that of amplifying circuit A^2 is 18 miles. Thus the net gain in branch A at the highest frequency involved is 45 miles. These gains correspond to potential differences between input and output terminals of 0.027 volts in filter section FA^1 , 0.008 volts for equalizer elements EA, 4.5 volts for amplifying structure A^1 , 1.2 volts for filter element FA^2 , 24.15 volts for amplifying structure A^2 , and 2.8 volts for filter section FA^3 . It is thus seen that if the entire amplification were obtained in one amplifying structure, the differences in voltage would amount to 28.65 volts.

While the invention has been specifically described as embodied in a carrier current repeater, the invention is applicable to other kinds of transmission employing high gain repeaters. The scope of the invention is to be limited only by the appended claims.

What is claimed is:

1. In an amplifying device, a plurality of three electrode-electron discharge devices connected in parallel, a source of polarizing potential for each of said devices, and means to confine the individual polarizing potentials to the respective individual devices. 100

2. In a repeater, a plurality of electron discharge devices, a cathode, an anode, and an impedance controlling element for each of said devices, a source supplying current which is to be amplified, means to connect said impedance controlling elements in parallel with one another with respect to said source, means to connect said cathode and said impedance controlling elements to said source, an output circuit including said cathodes and anodes, means to supply individual polarizing potential to each of said impedance controlling elements, and means to prevent the polarizing potential of each impedance controlling element from affecting that of any other impedance controlling element. 115

3. In a repeater, a plurality of electron discharge devices, a filamentary cathode, an anode, and a grid for each of said devices, a source supplying current to be amplified, means to connect said filamentary cathodes in series with each other and to said source, means to connect said grids in parallel to said source, an output circuit including said filamentary cathodes and anodes, means to apply individual polarizing potentials to each of said grids and a condenser connected in circuit between said grids. 125

4. In a repeater, a plurality of electron 130

- discharge devices, a cathode, an anode, and an impedance controlling element for each of said devices, a source supplying current to be amplified, means to connect said cathodes in series and said impedance controlling elements in parallel respectively to said source, an output circuit including said cathodes and anodes, a source of polarizing potential common to all of said devices 5 adapted to supply potentials of different values, independent circuits from said common source to each of said impedance controlling elements, and means to prevent the polarizing potential of each impedance controlling element from affecting that of any other impedance controlling element.
5. In a repeater, a plurality of pairs of three electrode electron discharge devices, each pair of devices connected in push-pull 10 arrangement with respect to each other and in parallel with said other pairs, a source of negative polarizing potential for each of said devices, and means to confine the polarizing potentials to respective individual 15 pairs of devices.
6. In a repeater, a plurality of pairs of three electrode electron discharge devices, each pair of devices connected in push-pull 20 arrangement with respect to each other and in parallel with said other pairs, a source of negative polarizing potential for each of said devices, and means to confine the polarizing potentials to respective individual 25 pairs of devices.
7. A repeater station, a line incoming to said station and a line outgoing from said station, a plurality of amplifying structures each individually mounted, a plurality of filters each adapted to transmit with negligible attenuation the frequencies to be amplified by said amplifying structures and to 30 highly attenuate all other frequencies, mounting means for the elements of said structures and said filters, said structures and said filters being so arranged on said mounting means that a filter is intermediate 35 each two repeater elements, and connections between said repeater structures and said filters so arranged that the input connections of one repeater structure are separated 40 from the output connections of an adjacent 45 repeater structure.
- In witness whereof, I hereunto subscribe my name this 26 day of January A. D., 1923.
- JACOB S. JAMMER.
